(57) **CLAIM**

The ornamental design for a hand care sheet, as shown and described.

DESCRIPTION

FIG. 1 is a perspective view of a hand care sheet according to the design;

FIG. 2 is a front view thereof; the rear view being a mirror image thereof;

FIG. 3 is a right side view thereof, the left side view being a mirror image thereof;

FIG. 4 is top plan view thereof;

FIG. 5 is a bottom plan view thereof;

FIG. 6 is an exploded perspective view thereof, wherein the sheets are separated; and,

FIG. 7 is a perspective view thereof, shown in an environment of use.

The broken line disclosure of a human hand illustrates environmental subject matter only and forms no part of the claimed design.

1 Claim, 4 Drawing Sheets
